Primary Examiner — Mojtaba Tehrani(74) *Attorney, Agent, or Firm* — Antoinette M. Tease(57) **CLAIM**

The ornamental design for an optic mount for rifle, as shown and described.

DESCRIPTION

FIG. 1 is a top perspective view of an optic mount for rifle showing the new design.

FIG. 2 is a bottom perspective view of an optic mount for rifle showing the new design.

FIG. 3 is a top view of an optic mount for rifle showing the new design.

FIG. 4 is a bottom view of an optic mount for rifle showing the new design.

FIG. 5 is a first side view of an optic mount for rifle showing the new design.

FIG. 6 is a second side view of an optic mount for rifle showing the new design.

FIG. 7 is a rear view of an optic mount for rifle showing the new design; and,

FIG. 8 is a front rear view of an optic mount for rifle showing the new design.

The broken lines are to show environmental structure only and form no part of the claimed design.

1 Claim, 3 Drawing Sheets(56)
